(57) **CLAIM**

I claim the ornamental design for a remote control vehicle, as shown and described.

DESCRIPTION

FIG. 1 is a front perspective view of a remote control vehicle.

FIG. 2 is a rear perspective view of a remote control vehicle. FIG. 3 is a side view of the left side of the remote control vehicle of FIG. 1.

FIG. 4 is a side view of the right side of the remote control vehicle of FIG. 1.

FIG. 5 is a top view of the remote control vehicle of FIG. 1.

FIG. 6 is a bottom view of the remote control vehicle of FIG. 1.

FIG. 7 is a front view of the remote control vehicle of FIG. 1; and,

FIG. 8 is a rear view of the remote control vehicle of FIG. 1.

The dashed lines in various figures are for illustrative purposes only and form no part of the claimed design.

The dashed broken lines shown represent portions of a remote control vehicle and form no part of the claimed design.
